United States Patent Office

Des. 216,158
Patented Nov. 25, 1969

216,158

SCAFFOLD SUPPORT OR THE LIKE

James R. Williams, 1816 Peters Road,
Irving, Tex. 75060

Filed Aug. 5, 1968, Ser. No. 13,142

Term of patent 14 years

Int. Cl. D8—99

U.S. Cl. D54—1

FIGURE 1 is a side view of the scaffold support or the like;

FIGURE 2 is a perspective view partially broken away;

FIGURE 3 is a fragmentary view of the top portion thereof in use with portions of a roof beam, wall stud and joist shown in broken lines for illustrative purposes only.

I claim:

The ornamental design for a scaffold support or the like, as shown and described.
